[57] CLAIM

The ornamental design for adjustable lighting fixture, as shown and described.

DESCRIPTION

FIG. 1 is a top plan view of a first embodiment of a adjustable lighting fixture according to new design;

FIG. 2 is a bottom plan view of the fixture;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a left perspective view thereof with the head in a different position;

FIG. 8 is a right perspective view thereof with the head in a different position;

FIG. 9 is a top plan view of a second embodiment of a adjustable lighting fixture according to new design;

FIG. 10 is a bottom plan view fixture;

FIG. 11 is a front elevational view thereof;

FIG. 12 is a left side elevational view thereof;

FIG. 13 is a rear elevational view thereof;

FIG. 14 is a right side elevational view thereof;

FIG. 15 is a left perspective view thereof with the head in a different position; and,

FIG. 16 is a right perspective view thereof with the head in a different position.
